UNITED STATES PATENT OFFICE.

HARRY C. BREWSTER, OF SHREVEPORT, LOUISIANA.

OIL-WELL-DRILLING MACHINE.

Application filed August 31, 1921. Serial No. 497,207.

To all whom it may concern:

Be it known that I, HARRY C. BREWSTER, a citizen of the United States, and a resident of Shreveport, in the parish of Caddo and State of Louisiana, have invented certain new and useful Improvements in Oil-Well-Drilling Machines, of which the following is a specification.

An important object of this invention is to provide a drilling machine having simple means whereby one of the sections of the drill stem may be rotated with relation to the other sections.

A further object of the invention is to provide a well drilling mechanism embodying inner and outer tables and means for holding the inner table against rotation so that the outer table which is operatively connected with the upper section of the stem or casing by means of tongs or the like may be turned with relation to the lower section of the stem or casing, which is held against rotation by the inner table.

Other objects and advantages of the invention will be apparent during the course of the following description.

In the accompanying drawings forming a part of this application and in which like numerals are employed to designate like parts throughout the same,

Figure 1 is a plan view of the improved drilling mechanism,

Figure 2 is a perspective of the inner table holding member which is carried by the bed or base of the drilling mechanism,

Figure 3 is a bottom plan view of the improved drilling mechanism,

Figure 4 is a vertical longitudinal sectional view through the same,

Figure 5 is a horizontal sectional view taken on line 5—5 of Figure 4,

Figure 6 is a perspective of one of the members employed for holding the inner table against rotation with relation to the outer table, and

Figure 7 is a perspective of a gripping member embodied in the invention.

Figure 8 is a group perspective of a retaining bushing.

In the drawings, wherein for the purpose of illustration is shown a preferred embodiment of the invention, the numeral 10 generally designates a bed or base having spaced parallel skids or runners 11 arranged on opposite sides of a well so that

the mechanism carried thereby may be engaged with the sections of the stem 12 extended into the well in the usual manner.

As illustrated in Figure 1, a metallic base plate 14 is secured upon the skids 11 by fastening devices 15 and supports a power transmitting shaft 16. One end of the power transmitting shaft 16 is provided with a sprocket wheel 17 having connection with a sprocket chain 18' extended from a suitable source of power. A clutch is mounted on the shaft 16 and consists of coacting sections 18 and 19 which when joined as illustrated in Figure 1, establish a driving connection between the sprocket wheel 17 and the shaft 16. The section 18 is rotatable on the shaft 16 while the section 19 is provided with longitudinally extending ribs 20 which non-rotatably but slidably support the section 19 on the shaft. The section 19 is moved longitudinally on the shaft 16 by means of a yoke 22 having connection with an operating lever 23 of any desired construction. It will be seen that when the section 19 is disengaged from the section 18, the driving connection between the sprocket wheel 17 and the shaft 16 will be broken.

With reference to Figure 4, it will be observed that a pinion 25 mounted on one end of the shaft 16 is engaged with an annular series of gear teeth 26 formed on the lower side of an outer table 27. The outer table 27 may when desired be operatively connected to the upper section of the drill stem by means of tongs or the like so that the rotation of the outer table will result in the rotation of the fluted upper section of the drill stem.

An inner table 30 is extended into a centrally arranged opening in the outer table 27 and may be locked to the outer table for rotation therewith by means of radially movable locking bars 32 slidable in radial slots 33 in the outer table. The bars 32 of which there may be two, are provided with outwardly directed adjusting pins or studs 34 which extend out through the upper surface of the outer table 27 so that the same may be conveniently engaged for adjusting the bars 32. With reference to Figure 4, it will be seen that the locking bars 32 are extended into sockets 36 formed in the inner table 30 whereby to cause the inner table to rotate with the outer table when desired.

When desired, the inner table may be released from driving engagement with the outer table and may be locked to the bed 10 and thereby held in a stationary position. 5 The lower portion of the inner table is squared to provide oppositely arranged shoulders 38 which are adapted to be flatly engaged by the opposed edges of an inner table locking member generally designated 10 by the numeral 39. Figure 2 illustrates that the table locking member 39 is of U-shaped formation and is provided with spaced parallel side arms 40, the inner edges of which are adapted to flatly engage the opposite 15 sides 38 of the inner table 30. When the flat inner edges of the arms 40 are flatly engaged with the sides 38, the inner table 30 is locked to the base and the outer table 27 is rotated independently of the inner 20 table. However, when it is desired to release the positive engagement between the inner table and the base, the holding member 39 is moved longitudinally so as to dispose recessed portions 42 in the arms 40 on 25 opposite sides of the flat shoulders or side walls 38 and thereby permit the inner table to rotate. The connecting portion 43 of the U-shaped member 39 defines a handle by means of which the holding member may be 30 moved longitudinally in the guides 45 which support the same.

As illustrated in Figure 4, an anti-friction element 46 of any desired style may be confined between the inner and outer tables so 35 as to permit the tables to be rotated with relation to each other.

In operation, the outer table can be locked to the inner table while turning the drill stem or casing. This is accomplished by 40 engaging the locking bars 32 with the inner table and subsequently rotating the outer table by imparting a rotary motion to the pinion 25.

When desired, the inner table may be 45 locked to the base and to the lower portion of the stem and a rotary motion may be imparted to the outer table 27 for causing the upper section of the drill stem to rotate. The lower section of the drill stem may be locked 50 to the inner table by means of a pair of semi-circular holding members 60 which as illustrated in Figure 7 have their inner sides formed with teeth 61 adapted to bite into the upper portion of the lower section 12. It 55 will be seen that the inner side of the inner table is tapered toward its lower end so that the holding members 60 are wedged into position for holding the lower section 12 firmly in place. Handles 62 of any desired type 60 may be connected to the upper ends of the holding members 60 to afford a means whereby the same may be readily removed when desired. The upper fluted portion of the drill stem may be locked to the upper portion 65 of the inner table by means of a retaining

bushing consisting of a pair of semi-circular sections 65 each of which is provided at its upper end with oppositely directed ears 66 adapted for the reception of fastening devices employed for connecting the sections 70 65. As illustrated in Figures 4 and 8 the sections 65 are engaged with opposite sides of the upper fluted portion of the drill stem and have their inner sides provided with grooves 67 to snugly receive the ribs of the 75 upper fluted portion and thereby hold the upper fluted portion against rotation with relation to the inner table.

It will be observed with reference to Fig. 8 that the laterally projecting ears 66 are 80 formed at the upper ends of oppositely directed ribs 68 which are received within grooves 69 in the bore of the inner table 30. The ribs 68 provide a driving connection between the sections 65 and the inner table so that when the inner table is positively rotated the fluted sections will also be rotated.

With reference to the foregoing, it will be seen that the holding members 60 are employed when it is desired to establish a driving connection between the lower portion of the drill stem and the inner table. When it is desired to establish a driving connection between the upper fluted portion of the stem and the inner table, the retaining bushings 95 65 are employed. As previously stated, the inner table may be locked against rotation by means of the member 39 and the outer table may be rotated for screwing or unscrewing the upper fluted portion of the 100 drill 10.

I claim:—

1. A drilling rotary comprising a bed, inner and outer tables associated therewith, a locking bar slidably carried by one of the 105 tables, the other table being provided with a socket to receive said locking bar whereby to lock the tables together, and means carried by the bed to lock one of the tables against rotation and consisting of a slidable member having spaced table engaging arms.

2. A drilling rotary comprising a bed, inner and outer tables associated therewith, a locking bar slidably carried by one of the 110 tables, the other table being provided with a socket to receive said locking bar whereby to lock the tables together, and means carried by the bed to lock one of the tables against rotation and consisting of a slidable member having spaced table engaging arms, said 120 arms being formed with table receiving recesses.

3. A well drilling mechanism comprising a bed, a table rotatably carried thereby and having flat sides, a U-shaped locking member having spaced parallel side arms adapted to flatly engage the sides of said table to hold the table against rotation.

4. A well drilling mechanism comprising a bed, a table rotatably carried thereby and 130

having flat sides, a U-shaped locking member having spaced parallel side arms adapted to flatly engage the sides of said table to hold the table against rotation, the intermediate portions of said side arms being provided with recesses to partially receive said table whereby to permit the same to rotate.

5. A well drilling mechanism comprising a bed, a table rotatably carried thereby and having flat sides, a U-shaped locking member having spaced parallel side arms adapted to flatly engage the sides of said table to hold

the table against rotation, and a second table receiving said first named table.

6. A well drilling mechanism comprising 15 a bed, a table rotatably carried thereby and having flat sides, a U-shaped locking member having spaced parallel side arms adapted to flatly engage the sides of said table to hold the table against rotation, a second table receiving 20 said first named table, and means carried by said second named table to lock said first named table thereto.

HARRY C. BREWSTER.
